US00D896263S

(12) **United States Design Patent** (10) **Patent No.:** **US D896,263 S**
(45) **Date of Patent:** **** Sep. 15, 2020**

(54) **DISPLAY SCREEN OR PORTION THEREOF WITH A GRAPHICAL USER INTERFACE**

(71) Applicant: **Beijing Microlive Vision Technology Co., Ltd.**, Beijing (CN)

(72) Inventor: **Peiwen Fang**, Beijing (CN)

(73) Assignee: **Beijing Microlive Vision Technology Co., Ltd.**, Beijing (CN)

(**) Term: **15 Years**

(21) Appl. No.: **29/693,657**

(22) Filed: **Jun. 4, 2019**

(30) **Foreign Application Priority Data**

Dec. 11, 2018 (CN) 2018 3 0717286

(51) **LOC (12) Cl.** **14-04**

(52) **U.S. Cl.**

USPC **D14/486**; D14/488

(58) **Field of Classification Search**

USPC D14/485-495

CPC G06F 3/048; H04M 1/72519-72561

See application file for complete search history.

(57) **CLAIM**

I claim the ornamental design for a display screen or portion thereof with a graphical user interface, as shown and described.

DESCRIPTION

The FIGURE is a front view of a display screen or portion thereof with a graphical user interface showing the new design.

The broken lines shown in the FIGURE represent portions of the display screen or portion thereof with a graphical user interface that form no part of the claimed design.
